BUOYANT BELT

Edgar G. Baker, Carbondale, Pa., assignor to Gентex
Corporation, New York, N.Y., a corporation of
Delaware

Filed Jan. 8, 1962, Ser. No. 68,230

Term of patent 14 years

(Cl. D71—1)

FIGURE 1 is a front perspective view of a buoyant belt showing new design.

FIGURE 2 is a rear elevational view thereof.

FIGURE 3 is a side elevational view thereof.

FIGURE 4 is an end elevational view thereof, the opposite end not shown being substantially the same in appearance.

I claim:

The ornamental design for the buoyant belt, substantially as shown and described.
